The ornamental design for a soccer goal wall, as shown and described.

DESCRIPTION

FIG. 1 is a front view of a soccer goal wall;

FIG. 2 is a perspective view thereof;

FIG. 3 is another perspective view thereof;

FIG. 4 is a left side view thereof;

FIG. 5 is a right side view thereof;

FIG. 6 is a rear view thereof;

FIG. 7 is a bottom view thereof; and,

FIG. 8 is top view thereof.

The broken lines in FIG. 6 represent portions of the article not claimed and form no part of the claimed design.

1 Claim, 6 Drawing Sheets(56)
